CONNECTOR SUPPORT ASSEMBLY FOR TRANSISTOR CONNECTOR AND METHOD OF MAKING THE SUPPORT ASSEMBLY

Ralph L. Sherwood, Westfield, and Daniel C. Hughes, Jr., Somerville, N.J., assignors to the United States of America as represented by the Secretary of the Air Force

Filed July 24, 1964, Ser. No. 385,095
3 Claims. (Cl. 29—155.5)

This invention relates to a throwaway jig and connector supporting assembly for the connectors to a transistor and the method of making the connector support assembly.

One object of the invention is to provide a support for the connectors for use with transistors that will ease the assembly operation.

Another object of the invention is to provide a support for the connectors for use with transistors that will simplify and decrease the cost of assembly of transistors.

These and other objects will be more fully understood from the following detailed description taken with the drawings wherein:

FIG. 1 shows a plan view of the throwaway jig and connector support device of the invention;

FIG. 2 is a sectional view of the device of FIG. 1 along the line 2—2;

FIG. 3 shows the mask used for preparing the upper surface of the device of FIG. 1;

FIG. 4 shows the mask used for preparing the lower surface of the device of FIG. 1; and

FIG. 5 shows the device of FIG. 1 as it is used in connecting the leads to the transistor.

In the assembly of most transistor devices it is necessary to make various connections between the crystal or pellet of the transistor and the wire leads. These connections are generally made with various wire forms.

According to this invention a number of connectors, arranged to suit the geometry of the device with which they are to be used are supported on an alignment device or jig. Shear holes and breakaway supports are provided so that the connectors can be separated from the alignment device after the connectors are secured to the transistor and the wire leads.

With reference to FIG. 1 of the drawing reference number 10 shows a support jig and connector assembly having a support 11 and alignment holes 12, 13 and 14. An emitter connector 15 is supported on the support 11 at 16. The base connector 17 is supported at 18 and the collector connector 20 is supported by a pair of breakaway support strips 21 and 22. Shear holes 23 and 24 are provided in the emitter and base leads 15 and 17 respectively.

In making the device of FIG. 1 a photosensitive resist 30 is coated on one side of steel sheet 26 which may, for example, be stainless steel. The sheet is then masked with the mask 31 shown in FIG. 3 and exposed. The unexposed portions are then removed by washing and gold is electro-formed onto the exposed areas to the desired thickness. The back of the steel plate 26 is then coated with a photosensitive resist 34, masked with mask 35, having an area corresponding generally to the area of the electrodes except for the area of the supports at 16, 18 and portions of support strips 21 and 22, shown in FIG. 4. The back coating is then exposed. The unexposed

2

portions corresponding to areas 37, 38, 39, 40 as shown on mask 35 are then removed by washing. The assembly is then subjected to an etchant such as ferric chloride which attacks the stainless steel but has no effect on the gold. The etching removes the stainless steel material in the holes and under the three gold connectors. The support and connector assembly is then ready for use.

The device is used as shown in FIG. 5. The jig and connector assembly is aligned over the transistor 42, by aligning holes 12, 13 and 14 on a fixture, not shown. The emitter and base connectors 15 and 17 are resistance welded to the wire leads 43 and 44 respectively and the collector connector 20 is resistance welded to the top of collector lead 46. The connectors 15, 17 and 20 are then sheared from support 11 at shear holes 23 and 24 and support strips 21 and 22. The connectors are then bonded to the transistor. The support 11 which remains is discarded as scrap.

There is thus provided a jig and connector support assembly for the connectors of a transistor.

While a certain specific embodiment has been described in detail it is obvious that numerous changes may be made without departing from the general principles and scope of the invention.

We claim:

1. A throwaway jig and connector support assembly for the connectors of a transistor: comprising a steel support member; a plurality of alignment holes in said steel support member; an opening substantially centrally located in said support; gold emitter and base transistor connector members, supported on said steel support member, projecting into said opening; said emitter and base connector members having shear holes therein whereby said connectors may be removed from said support member; a gold collector connector member projecting into said openings and a plurality of breakable tab means supporting said collector connector member on said support member adjacent said opening.

2. The method for making a connector support assembly for the connectors of a transistor comprising: coating one surface of a steel support member with a photosensitive resist; masking said photosensitive resist with a mask having the desired opaque electrode and electrode support pattern thereon; exposing said photosensitive resist to light to harden the unmasked regions; washing the unhardened coating from the masked regions; electro-forming gold onto the steel support member in the uncoated regions; coating the back surface of said steel support with a photosensitive resist; masking the photosensitive resist on the back of said support member with a mask having areas corresponding to a plurality of alignment holes and an area corresponding generally to the area of said connectors except for small support portions; exposing said photosensitive resist to light to harden the unmasked regions; washing the unhardened coating from the masked regions; and etching the exposed areas of the steel support with ferric chloride etch.

3. The method for providing connectors for a transistor comprising: coating one surface of a steel support member with a photosensitive resist; masking said photosensitive resist with a mask having the desired opaque electrode and electrode support pattern thereon; exposing said photosensitive resist to light to harden the unmasked regions; washing the unhardened coating from the masked regions; electro-forming gold onto the steel

support member in the uncoated regions; coating the back surface of said steel support with a photosensitive resist; masking the photosensitive resist on the back of said support member with a mask having an area corresponding generally to the area of said connectors except for small support portions and areas corresponding to a plurality of alignment holes; exposing said photosensitive resist to light to harden the unmasked regions; washing the unhardened coating from the masked regions; etching the exposed areas of the steel support with ferric chloride etch; resistance welding said connectors to the

wire leads of a transistor; shearing said support from said connectors and bonding said connectors to corresponding regions of the transistor.
